UNITED STATES PATENT OFFICE.

WILLIAM McCCLAVE, OF SCRANTON, PENNSYLVANIA, ASSIGNOR TO McCCLAVE-BROOKS COMPANY, OF SCRANTON, PENNSYLVANIA, A CORPORATION OF PENNSYLVANIA.

PNEUMATIC CONVEYER SYSTEM.

1,076,989.

Specification of Letters Patent.

Patented Oct. 28, 1913.

Application filed September 28, 1911. Serial No. 651,790.

To all whom it may concern:

Be it known that I, WILLIAM McCCLAVE, a citizen of the United States, residing at Scranton, in the county of Lackawanna and State of Pennsylvania, have invented certain new and useful Improvements in Pneumatic Conveyer Systems; and I do hereby declare the following to be a full, clear, and exact description of the same, reference being had to the accompanying drawings, forming part of this specification, and to the figures and letters of reference marked thereon.

This invention relates to pneumatic conveyer systems, and is particularly designed for use as a part of a mechanism for handling ashes from a battery of furnaces.

In systems to which the invention is particularly adapted for use, the ashes from the furnaces drop or are dumped into a conveyer duct and are transported through the duct and discharged therefrom into a suitable settling chamber by an elastic fluid medium, which may be compressed air or steam from the boilers. Conveniently, and in the preferred system to which the invention is adapted, the elastic fluid medium is supplied from the boilers by means of jets directed longitudinally of the duct at suitable intervals. In systems of this character great difficulty has been experienced in properly confining and separating the discharged ashes, cinders, etc., from the conveying medium and permitting the medium to pass off into the atmosphere in a substantially dust freed condition, and it is one of the objects of the present invention to provide a means whereby the ashes, cinders, etc., may be caught and settled into a more or less compact mass which can be readily handled mechanically and the air or gases discharged separate therefrom. The form of the apparatus is such as to occupy but a small area, and at the same time the walls of the receiving chamber will be effectually protected from the scouring and cutting action of the discharged material.

Referring to the accompanying drawings, Figure 1 is a sectional elevation showing the discharge end of a duct and the building into which the materials are discharged and wherein the separation of the solid from the gaseous materials is effected; Fig. 2 is an elevation from a point of view at the right of Fig. 1; Fig. 3 is a section in

a horizontal plane indicated by the line 3-3, of Fig. 2; Fig. 4 is an elevation corresponding to the elevation in Fig. 2, but showing a modified arrangement of the parts especially adapted for use where a more complete separation of the fine solid and gaseous materials is desired; Fig. 5 is a section in the horizontal plane indicated by the line 5-5 of Fig. 4.

Like letters of reference in the several figures indicate the same parts.

In said drawings, the letter A indicates a conveyer duct preferably formed of cast metal sections and which in its substantially horizontal portion passes along in front of a battery of boilers, one of which is indicated at B in Fig. 1. It is provided with suitable valved openings, not shown, for the reception of ashes from the ash pits of the boilers. At suitable points indicated at C, forwardly directed jet nozzles D enter the duct and are adapted for the admission of an elastic fluid medium such as steam from the boilers, whereby any material dumped into the duct will be drawn or forced through and discharged from the duct. In accordance with the present invention, the duct is curved upwardly, and at its terminal is directed vertically so that material discharged therefrom will be discharged vertically and as a result its momentum will be checked and practically overcome by the action of gravity without said material being allowed to strike the confining walls of the chamber into which it is discharged.

In order to reduce the area occupied by the receiving chamber and to deposit the solid materials at such height that they may readily drop by gravity into suitable vehicles for transportation to their point of ultimate deposit, the receiving chamber is of considerable height and of comparatively small area in a horizontal plane. The walls E of the chamber are preferably rectangular, of masonry construction, but braced and bound together by ties or eye or channel beams e, e'. At a suitable height in the chamber thus formed there is provided an inclined floor F which may be of reinforced concrete construction and which extends out through a discharge opening G to form a spout F', whereby the solid materials may be directed into a vehicle which is run under the spout. The openings G are preferably

closed by gates G' having counterweights g to facilitate the freedom with which they may be opened and closed.

The conveyer duct A passes up through the inclined floor F and to a sufficient distance above the same to insure its discharge end being always above any mass of material deposited in the chamber and in the preferred construction the discharge end of the duct is in proximity to one of the walls E of the chamber. It may be located centrally of said wall, as indicated in Figs. 1 and 2, or to one side of the center, as indicated in Fig. 4, for the purpose to be presently explained. The chamber into which the material is discharged from the duct and which may be termed a "settling chamber," extends for a considerable distance above the discharge end of the duct, thereby forming an unobstructed space into which the material may be discharged upwardly, but for the purpose of guiding the currents set up by the discharge of both the solid and gaseous materials, as well as to prevent the formation of eddying currents which would retard the settling of the solid material, a deflector plate is provided which extends from a point over and some distance above the discharge end of the duct in a curved path to the opposite side of the chamber. This deflector plate is indicated at H , and it may be conveniently supported on the walls E and from the top or cover I of the settling chamber. There is also provided a downwardly extending apron H' , adapted to protect the inner face of the wall E from abrasion of the material discharged from the duct, although in the form of apparatus contemplated by the present invention, there is no direct impact of the material against either the surface of the wall or against the protecting plate, and any material which contacts therewith is traveling practically in the plane of the surface with which it contacts.

By the construction just described, it will be noted that the material forcibly discharged from the duct will have its momentum constantly checked by the action of gravity, and the currents set up by the discharged material while tending upwardly immediately over the duct discharge, will be directed to the opposite side of the chamber and downwardly by the top deflector. Under the combined action of the deflector and gravity, the solid material will move to the opposite side of the chamber from the duct and will rapidly settle to the bottom of the chamber away from any disturbing air currents.

For the purpose of carrying off the gases from which the solid materials have settled the sides of the chamber are formed into vertical discharge stacks or flues indicated at K in Fig. 2, the inner walls of said flues

being supported on the transverse channel irons e' before referred to. In the construction shown in Figs. 1 and 2, both of the flues K open into or communicate with the settling chamber at a point well above the portion of the chamber which is adapted to contain the separated solid material, but below the portion of the chamber which extends upwardly for the purpose of permitting the momentum of the solid material being checked by gravity.

The cross sectional area of the chamber itself and of the flues K are such that the flow of air therethrough will be extremely slow and sluggish; in fact, it is intended to be so slow that even the finest solid particles will be permitted to settle out of the gases and drop down on the inclined floor F . In this connection it will be noted that the discharge flues K extend straight up from the lower portion of the settling chamber and have their lower ends entirely free and unobstructed so that material dropping from the gases and air passing up through the flues will drop freely and directly into the settling chamber itself, and will join the mass of solid material which is subsequently allowed to flow out through the discharge openings.

Where it is desired to effect a more complete separation of the gases and dust from the gases, than would be practical from the construction shown in Figs. 1 and 2, the arrangement shown in Figs. 4 and 5 is employed. In this arrangement, the duct A and deflector plate, lettered H^2 in this instance, are located slightly to one side of the center of the receiver, and one of the side flues, instead of being an upwardly discharging flue is in the form of what might be termed a diving flue; that is to say, at its upper end it opens into the separating and settling chamber at L , and at its lower end it opens into the space M below the inclined floor F , while the ultimate discharge flue K^2 leads from the space M upwardly, there being in this instance, preferably but one discharge flue, which corresponds in construction to one of the flues K , but is in communication with the space M below the floor F of the settling chamber, as indicated clearly in dotted lines in Fig. 4. In this construction the material discharged from the duct A into the settling chamber, will separate as in the former instance, but the exceedingly fine and impalpable dust which does not settle readily, will pass off and down through the flue L into the space M which is of considerable area, and in which it will have ample time to settle, as there will be no appreciable current of gases through the chamber. The gases will pass off freely through the flue K^2 freed from all solid material.

The construction of the apparatus is such

that it may be readily located in congested districts or in thickly built up communities, and at the same time the storage capacity may be made very large, whereby the necessity for carting away the ashes at frequent intervals is avoided.

It will be noted from Fig. 1 that the edge of the deflector H remote from the side below which the material is discharged from the duct is directed away from the wall at a slight angle whereby any material which may be caught by the deflector and its direction of motion changed will be directed downwardly away from the side wall so that the latter will be saved from abrasion. In the practical operation of the device, it is found that by discharging the material from the duct in an upward direction, the bottom of the settling chamber is kept practically free from all disturbing currents and, hence, there is no danger of material once settled being carried up into the air space. This effect is augmented and the settling of the material aided by the moisture supplied thereto during its transportation through the duct, as practice demonstrates that the steam will add sufficient moisture to the smaller particles to cause them to agglomerate slightly or, by increasing their weight, cause them to settle quickly to the bottom of the chamber.

Having thus described my invention what I claim as new and desire to secure by Letters Patent of the United States, is:

35 1. In a conveyer system, such as described, the combination with a relatively tall and narrow settling chamber having vertically disposed side walls, vertical discharge flues in the side walls and a bottom discharge for 40 solid material with a closure for said bottom discharge, of a duct through which the material is conveyed by the pressure of the elastic fluid medium, said duct having a vertically directed discharge end located in the 45 chamber at a point substantially midway of the height of the chamber, whereby a free and unobstructed space is left above the discharge end of the duct in which space the upward momentum of the solid material 50 will be checked by gravity, and a space will be left below the discharge end of the duct for the reception of the solid material.

55 2. In a conveyer system such as described, the combination with a relatively tall and narrow settling chamber having vertically disposed side walls, vertical discharge flues in the side walls and a bottom discharge for solid material with a closure for said bottom discharge, of a duct through which the 60 material is conveyed by the pressure of the elastic fluid medium, said duct having a vertically directed discharge end located in the chamber in proximity to one side wall and at a point substantially midway of the height of 65 the chamber, whereby a free and unob-

structed space is left above the discharge end of the duct in which space the upward momentum of the solid material will be checked by gravity, and a space will be left below the discharge end of the duct for the 70 reception of the solid material.

3. In a conveyer system such as described, the combination with a relatively tall and narrow settling chamber having vertically disposed side walls and vertical-discharge flues in the side walls with the entrance opening thereto at an intermediate point in the height of the chamber and a bottom discharge for solid material, of a duct through which the material is conveyed by the pressure of an elastic fluid medium, said duct having a vertically directed discharge end located in the chamber in proximity to one side wall, and at a point substantially midway of the height of the chamber, and a curved deflector extending from the side wall above said duct over to the opposite side wall, whereby air currents ascending along one of the side walls will be directed to and down the opposite side wall.

4. In a conveyer system such as described, the combination with a relatively tall and narrow settling chamber having vertically disposed side walls and vertical discharge flues in the side walls with the entrance opening thereto at an intermediate point in the height of the chamber and a bottom discharge for solid material, of a duct through which the material is conveyed by the pressure of an elastic fluid medium, said duct having a vertically directed discharge end, located in the chamber in proximity to one side wall, and at a point substantially midway of the height of the chamber, a curved deflector extending from the side wall above said duct over to the opposite side wall, whereby air currents ascending along one of the side walls will be directed to and down the opposite side wall, and a side wall protecting apron extending from the duct discharge to the lower edge of the deflector.

5. In a conveyer system such as described, the combination with a relatively tall and narrow settling chamber having vertically disposed side walls, oppositely disposed discharge flues in the side walls with their entrance openings at an intermediate point in the height of the chamber, said openings having their defining walls projecting into the chamber, whereby material gravitating in the chamber will pass without entering the opening, of a duct through which the material is conveyed by the pressure of an elastic fluid medium, said duct having a vertically directed discharge end located in the chamber in proximity to one side wall and intermediate the discharge flues, there being a free and unobstructed space both above and below said duct discharge, whereby the momentum of material blown into the chamber

- ber will be checked by gravity with a minimum securing of the walls and a storage place provided for the reception of the solid material below the duct discharge opening.
- 5 6. A settling chamber for conveying systems comprising a relatively long and narrow vertically arranged chamber provided with a curved deflector plate at the top and two vertical exhaust flues arranged in parallelism on opposite sides of the chamber, the entrance ends of said flues located substan-

tially midway of the height of the chamber, an inclined bottom for said chamber, a duct through which material is conveyed into the chamber having its outlet located high 15 above the upper end of the inclined bottom and between the entrance openings to the exhaust flues.
